UNITED STATES PATENT OFFICE.

JAMES NIGHTINGALE, OF NEW YORK, N. Y.

WOOD BLOCK FOR PAVING.

SPECIFICATION forming part of Letters Patent No. 606,574, dated June 28, 1898.

Application filed April 6, 1897. Serial No. 630,998. (No model.)

To all whom it may concern:

Be it known that I, JAMES NIGHTINGALE, a citizen of the United States, residing at New York, in the county of New York and State 5 of New York, have invented certain new and useful Improvements in Wood Blocks for Paving, of which the following is a specification, reference being had thereto to the accompanying drawings.

This invention relates to wood-block floors; and its object is to provide for the interlocking of the blocks one with another, for the direct keying of each block on the under or bottom side to the asphaltic or other mixture in which they are laid or bedded to the concrete or other similar foundation, and also for the anchoring of the floor directly to the substructure at convenient distances.

In the drawings, Figure 1 is a perspective view of one of the blocks. Fig. 2 is a plan view of several blocks as placed together. Fig. 3 is a sectional view longitudinally through one block and laterally of two adjacent blocks. Fig. 4 is a section showing an expansion-bolt employed. Fig. 5 is a lateral section of one of the blocks, showing the key for securing the block to the asphaltic mixture and cement foundation. Fig. 6 is a detail of the key.

In carrying out my invention each block is provided with rabbeted sides *b*, and underneath and completely back of these rabbeted side portions are further rabbets *b'* of triangular shape in cross-section. At each end 35 the block is provided with a tongue or projection *a*, narrower in width than the body of the block and in line with the rabbeted portion of the sides and adapted to engage with the rabbeted portion of the adjacent block when 40 the blocks are laid end to side, as indicated in Fig. 2. Underneath and back of the projecting tongues *a* are the angular rabbets *a'*, which are also triangular in cross-section.

Each block, as shown in Fig. 5, is provided 45 with a groove *c* of dovetail shape on the bottom side running lengthwise, and this groove receives the head of a metallic key *c'*, the lower half of said key entering the asphaltic mixture while in a semifluid state. This 50 asphaltic mixture (shown at B) sets or hardens around the lower extremity of the key, thereby securely fastening the blocks to the asphaltic mixture, as also to the cement foundation C, upon which the asphaltic mixture 55 is laid.

It will readily be understood that when the projections or tongues of one block engage under the rabbets in the sides of other blocks they will be firmly keyed together against independent upward movement. Further, the 60 triangular rabbets, which extend under and back of the rabbets in the sides and beneath and back of the tongues at the ends, will form dovetailed channels passing between the blocks and completely encircling each block, 65 and it will be observed that the dovetailed channels formed between adjoining sides are double the width of the channels between an end and side. The blocks will thus be firmly and securely locked in place by the asphaltic 70 or other suitable mixture entering these dovetailed channels *a' b'*, as plainly indicated in Fig. 3, and thus the blocks are secured individually by the keys and collectively at the margins by the mixture entering the grooves. 75

I find in practice that it is advisable to secure the flooring-blocks at convenient intervals directly to the concrete or other substructure in addition to the means described, and for this purpose use, as shown in Fig. 4, 80 an expansion-bolt D, the head of which may be countersunk in the block and the recess above it filled with a wood plug to correspond with the rest of the wood flooring, and these bolts may be placed at any desired portions 85 of the flooring as may be found most convenient.

It is obvious that by the tongue-and-shoulder engagement described the several blocks will be supported one by another, so that sagging, warping, twisting, and other unevenness in any part of the finished floor is entirely prevented, that would otherwise occur through disturbance caused by expansion and contraction and the like. 95

Having thus described my invention, what I claim is—

A wood block for floors having rabbeted sides, and angular rabbets underneath and back of the rabbeted sides, and having also 100 tongues at the ends adapted to be fitted to the rabbeted sides, and having also angular rabbets at the ends underneath and back of the tongues, substantially as described.

In testimony whereof I affix my signature 105 in presence of two witnesses.

JAMES NIGHTINGALE.
